CARRIER-WAVE GENERATING SYSTEM

Nelson P. Case, Great Neck, N. Y., assignor to
 Hazeltine Corporation, a corporation of Delaware

Application March 20, 1942, Serial No. 435,441

19 Claims. (Cl. 250—36)

The present invention relates to carrier-wave generating systems and, particularly, to such systems adapted to generate a carrier wave having any selectable one of a number of predetermined constant frequencies in a predetermined frequency band, each such frequency corresponding to a desired transmission channel.

It is frequently desirable to provide a high-frequency carrier-wave generating system capable of generating a carrier wave having a constant or stabilized frequency on any selectable one of a predetermined number of transmission channels located in a predetermined high-frequency band. Such systems have many useful applications. For example, in the field of marine communication, a predetermined number of transmission channels are allocated for use in ship-to-shore communication in the vicinity of a given port and, since the number of ships in that locality desiring to use such channels may exceed the number of channels assigned to such service, it would be undesirable to assign a particular channel to a given ship. A person having available the carrier-wave generating system of the type described can listen on the air to find a channel which is not used at that moment and may then quickly and readily set his transmitting apparatus for operation on a non-used channel.

There are only a limited number of radio transmission channels available in the portion of the frequency spectrum normally used at the present day. The demands upon the available channels necessitate that interchannel interference be reduced to a minimum by the use of carrier-wave generating systems having a high degree of frequency stability. Piezoelectric crystals are conventionally used for this purpose. Where the carrier-wave generating system must operate on any selectable one of a number of pre-determined transmission channels, the problem arises as how best to stabilize the frequency of the system on each of these channels. Individual crystals may, of course, be provided for each such channel. This has the disadvantage, however, that it requires a large number of relatively expensive crystals and requires a complicated switching arrangement by which the crystals are selectively included in circuit with the oscillator of the generating system.

In one arrangement of the prior art it has been proposed that multi-channel transmission be provided by the use of a relatively high-frequency carrier-wave generator, a tunable low-frequency oscillator which is relatively stable in absolute

frequency by virtue of the fact that it generates only low frequencies, a modulator by which the high-frequency carrier wave is modulated with the low-frequency generated oscillations to provide a modulated-carrier wave including a carrier-wave component and modulation sideband components, and a selector for selecting one sideband of the modulated-carrier wave to derive a modulation component which is used as the carrier wave for radiation. This prior art arrangement has several disadvantages. No provision is made for precisely tuning the generating system to definite predetermined transmission channels, this being done only by the method of manually tuning the low-frequency oscillator as closely as manual manipulation will permit to any desired channel. There is the further disadvantage that the system is capable of operating only over a very limited operating-frequency band. Additionally, there is the disadvantage that the selector which selects the desired sideband component of the modulated-carrier wave generally cannot, in practice, be designed to select only the desired component to the exclusion of the carrier-wave component and the other modulation sideband component, with the result that the latter components are apt to be radiated as undesired spurious carrier waves which may create undesired interference on other transmission channels.

30 In accordance with another prior art arrangement, it has been proposed that precise multiple-channel operation of a carrier-wave generator on definite selected transmission channels be provided by the use of a low-frequency crystal-controlled oscillator having a frequency equal to the frequency separation of desired transmission channels. There is derived from this oscillator a modulation signal having frequencies which are harmonically related to the frequency of the low-frequency oscillator. A high-frequency crystal-controlled oscillator generates a carrier wave which is modulated with the modulation signal to derive a carrier wave having modulation sideband components which define desired equally-spaced transmission channels. A selected component of the modulated-carrier wave is used as the carrier wave which is radiated. While this prior art arrangement is adapted to operate over a wide band of operating frequencies, it is subject, as in 40 the arrangement previously described, to the radiation of undesired modulation components as undesired spurious carrier waves. The radiation of such spurious carrier waves causes, of course, undesired interference with communications on 50 channels other than that which, at any given

time, is used by the carrier-wave generating system described.

It is an object of the present invention, therefore, to provide a new and improved carrier-wave generating system which avoids one or more of the disadvantages and limitations of the prior art systems.

It is a further object of the invention to provide an improved carrier-wave generating system in which a single frequency standard is effective to maintain the frequency of a relatively high-frequency carrier wave substantially constant on any selectable transmission channel in a wide band of such channels.

It is an additional object of the invention to provide a carrier-wave generating system adapted to generate a relatively high-frequency carrier wave and in which the frequency of the wave generated is manually adjusted approximately to that suitable for operation of the system on any selected transmission channel in a wide band of such channels and the generator is thereafter automatically controlled to adjust it more accurately to and maintain it on such selected channel.

It is a further object of the invention to provide a carrier-wave generating system in which a plurality of frequency standards are effective to establish and maintain the frequency of a relatively high-frequency carrier wave substantially constant on any selectable transmission channel in one of a plurality of wide bands of such channels after the frequency of the carrier wave has been manually adjusted approximately to the frequency corresponding to such selected channel, each of such bands of channels being defined by a particular one of the frequency standards and the transmission channels of one band intervening between the channels of at least a portion of one or more of the others of the bands.

In accordance with the invention, a carrier-wave generating system comprises means for generating a carrier wave including a carrier-wave component of relatively high and substantially constant frequency and sideband components of substantially constant frequency and extending over a predetermined frequency band. The system includes means for generating a second wave having any selectable frequency in a predetermined band equal to but displaced by a predetermined value in the frequency spectrum from the first-mentioned frequency band. There is also included in the system means responsive jointly to the frequency of the second wave and the frequency of that one of the aforesaid components of the first wave which is displaced in the frequency spectrum by a predetermined value from the desired operating frequency of the second wave for maintaining the frequency of the second wave at a substantially constant desired value.

For a better understanding of the present invention, together with other and further objects thereof, reference is had to the following description taken in connection with the accompanying drawings, and its scope will be pointed out in the appended claims.

Referring now to the drawings, Fig. 1 is a schematic circuit diagram of a complete carrier-wave generating system embodying the present invention; Fig. 2 is a frequency scale used as an aid in explaining the operation of the Fig. 1 arrangement; Fig. 3 is a schematic circuit diagram of a complete carrier-wave generator embodying a modified form of the invention; and Figs. 4 and 5

are frequency scales used in explaining alternative modes of operation of the Fig. 3 arrangement.

Referring now more particularly to Fig. 1 of the drawings, there is represented schematically a complete carrier-wave generating system embodying the present invention in a particular form. The system includes means for generating a carrier wave of high and substantially constant frequency comprising an oscillator 10, this means including means for maintaining the frequency thereof substantially constant comprising, preferably, a piezo-electric crystal 11. The system also includes means for generating a modulation signal having frequency components of substantially constant frequencies and predetermined frequency spacing relative to each other, preferably a frequency spacing equal to that between equally-spaced desired transmission channels, comprising an oscillator 12 and a harmonic generator 13 having an input circuit coupled to the output circuit of the oscillator 12. Since the frequency components of the modulation signal derived by the harmonic generator 13 are harmonically related, it will be seen that they have equal frequency spacings relative to each other and, as will become apparent hereinafter, define equally-spaced predetermined desired transmission channels. The system additionally includes means for modulating the carrier wave generated by oscillator 10 with the modulation signal generated by units 12 and 13 to derive a carrier wave including a carrier-wave component of relatively high and constant frequency and sideband components of substantially constant frequencies and extending over a predetermined frequency band. This last-named means comprises a modulator 14 having one input circuit coupled to the output circuit of harmonic generator 13 and another input circuit coupled to the output circuit of oscillator 10 and having an output circuit in which is developed the aforementioned carrier wave including the carrier-wave component and sideband components.

The carrier-wave generating system of the invention also includes means for generating a second wave having any selectable frequency in a predetermined frequency band equal to but displaced in the frequency spectrum from the frequency band of the above-mentioned modulated carrier wave, hereinafter referred to as the "control carrier wave" for simplicity, developed by units 10-14, inclusive. This means comprises an oscillator 15 having an adjustable tuning element comprising a condenser 16 for tuning the oscillator 15 approximately to a desired operating frequency. Since in practice it is desirable for numerous reasons, such as lower cost, the increased ease of making, and increased ruggedness, that the piezoelectric crystal 11 have a frequency as low as the circumstances permit, the frequency band of the oscillator 15 preferably lies above the frequency band of the control carrier wave.

There is also included in the carrier-wave generating system means responsive jointly to the frequency of the second wave, which is generated by the oscillator 15, and the frequency of that one of the frequency components of the control carrier wave which is displaced in the frequency spectrum by a predetermined selectable value from the carrier-wave component of the latter wave for maintaining the frequency of the second wave at a substantially constant desired value. This last-named means comprises a modulator 17 having a first input circuit coupled

to the output circuit of modulator 14 and a second input circuit coupled to the output circuit of oscillator 15, the modulator 17 having an output circuit coupled to an intermediate-frequency amplifier 18 of one or more stages. There is 5 coupled to the output circuit of amplifier 18, in the order named, a frequency detector 19 and a frequency shifter 20, which may comprise a reactor tube, coupled across a frequency-control circuit of oscillator 15. The output circuit of oscillator 15 is coupled to the input circuit of a unit 21 which may include an amplitude-modulator stage and a tunable radio-frequency amplifier of one or more stages. The modulation signal to be transmitted is applied to the modulator of unit 21 in conventional manner. The output of the radio-frequency amplifier of unit 21 is coupled to an antenna system 22, 23. The radio-frequency amplifier of unit 21 includes an adjustable tuning element 24 which is mechanically connected 10 to unicontrol operation with the adjustable tuning element 16 of oscillator 15, as indicated by the broken line 25.

Considering now the operation of the arrangement just described, and referring to the frequency scale of Fig. 2, assume that the carrier-wave generating system is to operate on any selectable one of a predetermined number of transmission channels having equal frequency spacing f_1 . The oscillator 12 generates oscillations having the frequency f_1 and, since this frequency is normally relatively low, for example of the order of 100 or 200 kilocycles, this oscillator has good absolute frequency stability without requiring that it be of the piezoelectric crystal-controlled type. If desired, however, the oscillator 12 may be of the crystal-controlled type to insure even better frequency stability.

The signal generated by the oscillator 12 thus has a frequency equal to the frequency spacing between the equally-spaced desired transmission channels and this signal is applied to the input circuit of the harmonic generator 13. There is derived in the output circuit of generator 13 a modulation signal having frequency components which may, for example, include the fundamental-frequency component f_1 of the signal of oscillator 12 and nine harmonic components f_2-f_{10} , inclusive, which are harmonically related to, and preferably, are a continuous band of harmonics of the signal generated by the oscillator 12, whereby the frequency components of the modulation signal have relative spacings corresponding to that of desired transmission channels. This modulation signal is applied to an input circuit of the modulator 14 and there is applied to another input circuit of this modulator a carrier wave having a relatively high and substantially constant frequency f_{11} generated by the oscillator 10.

There is consequently derived in the output circuit of the modulator 14 the control carrier wave including a carrier-wave component of relatively high and substantially constant frequency and sideband components of substantially constant frequency and extending over a predetermined frequency band, such components of the control carrier wave having, in the preferred form of the invention, equal spacing in the frequency spectrum with relation to each other and the frequency of the components individually defining predetermined desired transmission channels. The term "define" is here used to denote that these components individually so con-

trol the oscillator 15 that the frequency of the carrier wave generated by oscillator 15 at any given time corresponds to that of a selected one of a plurality of transmission channels equal in number to the components but lying in the frequency spectrum in predetermined relations with respect to the frequency band of the components, preferably lying above the latter band. The frequency components of this control carrier wave are indicated in Fig. 2 as a spectrum of frequencies shown over the frequency f_{11} and extending over a frequency band $f_{14}-f_{15}$, the carrier-wave component being designated by the frequency f_{11} , the lower-sideband components by the frequencies f_{10} to f_1 , inclusive, and the upper-sideband components by the frequencies f_{11}' to f_{10}'' , inclusive.

The control carrier wave is applied from modulator 14 to one input circuit of the modulator 17 while the carrier wave developed by the oscillator 15 is applied to another input circuit of the modulator 17. The oscillator 15 is tunable by manual adjustment of the tuning element 16 over a predetermined frequency band $f_{12}-f_{13}$ which is equal to but displaced in the frequency spectrum from the frequency band $f_{14}-f_{15}$ of the control carrier wave, preferably displaced above the latter band, the mean frequency of the band $f_{12}-f_{13}$ being designated as f_{17} . The carrier wave generated by the oscillator 15 may thus have any selectable frequency in this predetermined operating frequency band $f_{12}-f_{13}$. The frequency of the oscillator 10 is so chosen that the carrier-wave component f_{11} of the control carrier wave $f_{14}-f_{15}$ is below and at a predetermined frequency spacing f_{18} from the mean operating frequency f_{17} of the oscillator 15. The frequency spacing f_{18} is preferably chosen greater than one-half of the frequency range $f_{14}-f_{15}$ of the control carrier wave for reasons presently to be explained.

There is thus developed in the output circuit of modulator 17 in a manner well known, an intermediate-frequency control signal having the difference value of frequency f_{18} whenever the carrier wave of oscillator 15 has a frequency spaced by the frequency difference f_{18} from any of the sideband components $f_{11}-f_{10}$ or $f_{11}'-f_{10}''$ or the carrier-wave component f_{11}' of the control carrier wave $f_{14}-f_{15}$. This intermediate-frequency control signal is amplified in the amplifier 18 and applied to the frequency detector 19 to develop in the output circuit thereof a unidirectional control potential the magnitude and polarity of which vary, as in conventional automatic frequency-control systems, with the deviation and sense of deviation of the intermediate-frequency signal from the mean resonant frequency f_{18} to which the frequency detector is tuned. This derived unidirectional control potential is applied to the input circuit of the frequency shifter 20 so to control the action thereof, as by varying the simulated reactance of its reactor tube, that the frequency of the oscillator 15 is changed in such a direction and to such an extent that the frequency of the intermediate-frequency control signal is very nearly the value f_{18} . This action occurs, of course, each time that the oscillator 15 is so tuned that its frequency is approximately spaced by the frequency spacing f_{18} from any selected one of the components of the control carrier wave. Each time that the frequency of the oscillator 15 is so controlled, the frequency of the carrier wave generated thereby is maintained substantially constant on that one of the transmission

channels which is defined by the frequency component of the control carrier wave that produced the intermediate-frequency control signal. Thus, as the tuning control 16 of the oscillator 15 is varied continuously in one direction over its operating frequency range $f_{12}-f_{13}$, the carrier wave generated thereby is stabilized for intervals, depending upon the rate of such tuning, on predetermined transmission channels defined by each of the frequency components of the control carrier wave. In using the arrangement of Fig. 1, the oscillator 15 is manually tuned by adjustment of its tuning element 16 approximately to an operating frequency corresponding to a desired transmission channel and the units 18, 19 and 20 thereupon operate to establish and maintain the frequency of the oscillator 15 more accurately at the desired operating frequency and upon the desired transmission channel which, as pointed out, is defined by one of the frequency components of the control carrier wave f_{14} to f_{15} .

It will be understood, of course, that the band-pass characteristics of the intermediate-frequency amplifier 18 and frequency detector 19 are such that the automatic-frequency control system comprising units 18, 19 and 20 relaxes at least during some portion of the time required manually to tune the oscillator 15 by adjustment of its tuning element 16 from one transmitting channel to an adjacent channel. If this were not so, the oscillator 15 could not be tuned from any given channel to every other channel.

The carrier wave generated by the oscillator 15 is applied to the modulator included in unit 21 where, after amplitude modulation by the signal which it is desired to transmit, the modulated-carrier signal is amplified by the radio-frequency amplifier of this unit and applied to the antenna system 22, 23 for radiation therefrom.

In lieu of the use of an amplitude-modulator stage in unit 21 as described, the signal which it is desired to transmit may alternatively be applied to the frequency shifter 20 in conventional manner to frequency-modulate in accordance with such signal the carrier wave generated by the oscillator 15.

It has previously been stated that the frequency f_{11} of the oscillator 10 is spaced by the frequency difference f_{16} from the mean operating frequency f_{17} of the operating frequency band $f_{12}-f_{13}$ of the oscillator 15 and that the frequency spacing f_{16} is preferably greater than half the frequency band $f_{14}-f_{15}$ over which the components of the control carrier wave extend. This is desirable from the standpoint that there are then no components of the control carrier wave which can beat with the carrier wave of oscillator 15 to produce image-frequency control signals in the output circuit of the modulator 17. While such frequency spacing of the oscillator 10 is desirable, it is not essential and the frequency spacing may be less than one-half of the frequency range $f_{14}-f_{15}$. Where this is the case, however, the value of the frequency spacing f_{16} should be an odd multiple of one-quarter of the channel spacing defined by the frequency components of the control carrier wave. This insures that any image intermediate-frequency control signals which are produced by intermodulation between the carrier wave of oscillator 15 and nonselected components of the control carrier wave have frequencies sufficiently widely spaced from the desired control signal that they are not translated with appreciable amplitude by the amplifier 18 to the detector

10 18. Whatever small-intensity image signals that are applied to the detector 17, however, have frequencies such that the unidirectional control potential produced therefrom in the output circuit 5 of the detector 19 so controls the frequency of the oscillator 15 that the latter is tuned away from the one of such nonselected components which produces the largest-intensity image signal and, in being so tuned, is tuned toward the selected component.

15 The arrangement of Fig. 1 has the important advantage that the input circuit of the unit 21 is substantially completely decoupled from any of the units 10 to 14, inclusive, and, hence, the control carrier wave is substantially completely isolated from the input circuit of unit 21. Consequently, none of the frequency components of the control carrier wave can be translated through the unit 21 to the antenna system 22, 23 for radiation therefrom as spurious undesired carrier waves which would cause interference with communications carried on with other apparatus.

20 25 The band of transmission channels over which a carrier-wave generating system embodying the arrangement of Fig. 1 can be designed to operate depends, of course, upon the number of harmonic frequencies of reasonably large amplitude that can be derived by the harmonic generator 13 from the oscillations generated by the oscillator 12. 30 Where this limited number of transmission channels is inadequate for a particular purpose, the modified form of the invention represented by the schematic circuit diagram of Fig. 3 is useful. The arrangement of Fig. 3 is essentially similar to that of Fig. 1, similar circuit elements being designated by similar reference numerals and analogous circuit elements by similar reference numerals primed. The arrangement of Fig. 3 differs from that of Fig. 1 in that it comprises means including 35 at least one oscillator having means for maintaining the frequency thereof substantially constant, preferably at least one piezoelectric crystal-controlled oscillator, for generating a plurality of carrier waves each including a carrier-wave component of relatively high and substantially constant frequencies and sideband components of substantially constant frequencies and extending over a predetermined frequency band. The frequencies of the components of each of such carrier waves individually define predetermined desired transmission channels. This means comprises an oscillator 10' having a plurality of piezoelectric crystal devices 11, 11', 11'', 11''', any selected one of which may be included in circuit 40 45 with the oscillator 10', by manual operation of the switch 26. The instant arrangement also includes selector means for selecting a desired one of the components of the control carrier waves, this means comprising a tunable selector 27 having an input circuit coupled to the output circuit of the modulator 14 and having an output circuit coupled to the input circuit of the modulator 17. The selector 27 includes an adjustable tuning element 28 which is connected for unicontrol operation 45 50 with the adjustable tuning elements 16 and 24 of the respective units 15 and 21, as indicated by the broken line 25'. The oscillator 15 in this arrangement is tunable over a predetermined operating-frequency band equal to, but displaced 55 in the frequency spectrum from, the combined frequency bands of the control carrier waves developed in the output circuit of the modulator 14. 60 65 Considering now the operation of this modified form of the invention, and referring to the frequency scales of Figs. 4 and 5, it may be stated 70 75

that, in general, its operation is essentially similar to that of Fig. 1 and will not be repeated in detail. There are two alternative manners in which the present arrangement may be used to extend the available number of transmission channels on which the system may operate. The first of these is illustrated in Fig. 4 wherein, for purposes of simplicity, only two control carrier-wave frequency spectra are shown. The carrier-wave component and sideband components of one control carrier wave, for example, that produced by the oscillator 10' under control of the piezoelectric crystal 11, extends over the range $f_{14}-f_{15}$, while the frequency of the carrier wave generated by the oscillator 10' under control of another of the crystals, for example the crystal 11', is so chosen that the components of the control carrier wave corresponding thereto extend over a higher frequency $f_{16}-f_{17}$, the adjacent end frequencies f_{15} and f_{16} of these two frequency ranges being spaced by the width of one transmission channel. The operating frequency band $f_{20}-f_{21}$ of the oscillator 15 is now equal to the combined frequency band $f_{14}-f_{17}$ of these two control carrier waves, and, actually to the combined frequency bands of all of the control carrier waves used in the system. The frequencies of the crystals 11 to 11''' inclusive, are additionally so chosen that the mid-range of the combined frequency band of the control carrier waves produced thereby is spaced by a frequency f_{23} from the mean operating frequency f_{22} of the operating frequency band $f_{20}-f_{21}$ of the oscillator 15. The operation of the Fig. 3 arrangement when operated in this manner is otherwise essentially similar to that of the Fig. 1 arrangement except that the desired component of a given control carrier wave is selected by the selector 27 and applied to the modulator 17 substantially to the exclusive of undesired image components thereof. The intermediate-frequency control signal developed in the output circuit of the modulator 17 has a frequency f_{23} in this instance and the units 18, 19 and 20 operate to establish and maintain substantially constant the frequency of the oscillator 15 on a selected one of the transmission channels defined by the control carrier-wave component which is utilized.

An alternative method of operating the Fig. 3 arrangement is illustrated by the frequency scale of Fig. 5. Here the harmonic components of the modulation signal generated by the harmonic generator 13 are more widely spaced than is the case in the arrangement of Fig. 1 and define every fourth desired transmission channel where there are four crystals used in the oscillator 10'. The frequencies of the crystals 11 to 11''' inclusive, are so chosen with relation to each other that the frequencies of the components of the control carrier wave produced by each individually define predetermined desired transmission channels but the channels defined by a given one of the control carrier waves are different from, and intervene between, at least a portion of the transmission channels defined by at least one other of the control carrier waves. The oscillator 12 in this case has a frequency corresponding to the spacing of four desired transmission channels, whereby the frequency spacing of the frequency components of the control carrier wave derived by unit 14 correspondingly define every fourth desired transmission channel. The frequencies of the crystals 11-11''' are so chosen with relation to each other that any crystal has a frequency displaced from the next preceding crystal

by an amount corresponding to one desired transmission channel. The control carrier wave developed in the output circuit of modulator 14 from the carrier wave of the oscillator 10' under control of the crystal 11, for example, is thus as indicated in Fig. 5 by the legend A; that corresponding to the crystal 11' by the legend B; that corresponding to the crystal 11'' by the legend C; and that corresponding to the crystal 11''' by the legend D. It will be seen that the components of the control carrier wave B are each displaced by one desired transmission-channel spacing from the corresponding components of the control carrier wave A. Similarly, the components of the carrier wave C are displaced from the corresponding components of the carrier wave B by one desired transmission-channel spacing, and the components of the control carrier wave D are similarly displaced from the corresponding components of the control carrier wave C.

In using the arrangement of Fig. 3 and the last-described mode of operation, one component of one of the control carrier waves A, B, C or D will define the transmission channel upon which it is desired to operate. Assuming that this is a component of the control carrier wave C, the switch 26 is adjusted to include the piezoelectric crystal device 11''' in circuit with the oscillator 10' to develop in the output circuit of modulator 14 the control carrier wave C. The adjustable tuning element 16 of the oscillator 15 is then adjusted approximately to the desired operating frequency and the mechanical connection between the adjustable tuning element 16 and the adjustable tuning element 28 of the selector 21 causes the latter tuning element simultaneously to be adjusted to condition the selector 21 to select the desired component of the control carrier wave C which defines the transmission channel upon which it is desired to operate. The selected component of the control carrier wave C is applied to one input circuit of modulator 17 to develop in the output circuit thereof an intermediate-frequency control signal having a frequency approximating frequency f_{23} . Units 18, 19 and 20 thereupon operate to control the frequency of the oscillator 15, as in the arrangement of Fig. 1, to establish and maintain the frequency of the carrier wave generated thereby more exactly on the desired transmission channel corresponding to the selected component of the control carrier wave. It will thus be evident that, by selection of one of the piezoelectric devices 11-11''' inclusive, and suitable adjustment of the tuning elements 24, 16 and 28, the carrier-wave generating system of Fig. 3 may be caused to operate on any desired transmission channel included in the frequency band over which the system is designed to operate. In this respect, it may be noted that the carrier wave generated by the oscillator 15 may have any selected frequency in a predetermined frequency band $f_{20}-f_{21}$, this band being equal to but displaced in the frequency spectrum from the combined frequency bands of the control carrier waves A, B, C and D. The operation of this modified form of the invention is otherwise essentially similar to Fig. 1 and will not be repeated.

While a tunable selector 21 has been included in the Fig. 3 arrangement, the use of this unit is not essential and the unit may be dispensed with, if desired, in which case the output circuit of modulator 14 is directly connected to one input circuit of the modulator 17. Furthermore a tunable selector similar to unit 21 may be included

in the arrangement of Fig. 1 between the modulator 14 and the modulator 17, if desired, and when so included will operate for the same purpose and in the same manner as the tunable selector 27 of the Fig. 3 arrangement. A selector of this nature is primarily useful where the mean frequency of the operating-frequency band over which the oscillator 16 is tunable is spaced from the frequency of the crystal 11 in the Fig. 1 arrangement or any of the crystals 11-11' in the Fig. 3 arrangement by less than one-half of the frequency band over which the components of the corresponding control carrier wave extend. In this event, the tunable selector prevents the application to the modulator 17 of such non-selected components of a control carrier wave as would produce image intermediate-frequency control signals in the output circuit of the modulator 17.

While it has previously been stated that the sideband components of the control carrier wave preferably have equal spacings in the frequency spectrum with relation to each other and to the carrier-wave component, it will be evident that only selected ones of the harmonic frequencies of the modulation signal generated by the harmonic generator 13 may be used. In this event, the sideband components of the control carrier wave may have unequal spacings with relation to each other, but nevertheless define desired unequally-spaced transmission channels. An arrangement of this nature, is useful, for example, where it is desired to transmit on, say, only the second, fifth, ninth and tenth transmission channels in a band of ten equally-spaced such channels.

From the above description of the invention, it will be apparent that a carrier-wave generating system embodying the invention is adapted to generate a carrier wave having a high degree of frequency stability and a frequency accurately corresponding to that of any selected one of a plurality of predetermined desired transmission channels. There is the further advantage in a system of this nature that there are produced no undesired spurious carrier waves which might cause interference with communications carried on by other persons on other channels. A carrier-wave generating system embodying the invention has the additional advantage that the frequency of the generated carrier wave may be and preferably is higher than that of a frequency standard used in the system. This is particularly important where the frequency standard comprises a piezoelectric crystal in which case it is desirable for numerous reasons, for example the lower cost of the crystal, its ruggedness, and the greater ease with which it may be manufactured, that the resonant frequency of the crystal be as low as the circumstances will permit.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A carrier-wave generating system comprising, means for generating a carrier wave including a carrier-wave component of relatively high and substantially constant frequency and sideband components of substantially constant frequencies and extending over a predetermined fre-

quency band, means for generating a second wave having any selectable frequency in a predetermined frequency band equal to but displaced by a predetermined value in the frequency spectrum from said first-named frequency band, and means responsive jointly to the frequency of said second wave and the frequency of that one of said components of said carrier wave which is displaced in the frequency spectrum by a predetermined value from the desired operating frequency of said second wave for maintaining the frequency of said second wave at a substantially constant desired value.

2. A carrier-wave generating system comprising, means for generating a carrier wave including a carrier-wave component of relatively high and substantially constant frequency and sideband components of substantially constant frequencies and extending over a predetermined frequency band, the frequency of said carrier-wave component and the frequencies of said sideband components being individually related to the carrier frequencies of predetermined desired transmission channels, means for generating a second wave having any selectable frequency in a predetermined frequency band equal to said first-named frequency band, and means responsive jointly to the frequency of said second wave and the frequency of one of said components of said carrier wave for maintaining the frequency of said second wave substantially constant on the one of said transmission channels related to said one component.

3. A carrier-wave generating system comprising, means for generating a carrier wave including a carrier-wave component of relatively high and substantially constant frequency and sideband components of substantially constant frequencies and extending over a predetermined frequency band, the frequency spacings of said sideband components with relation to each other and to said carrier-wave component being equal to predetermined corresponding frequency spacings of desired transmission channels whose operating frequencies are related to said components, means for generating a second wave having any selectable frequency in a predetermined frequency band equal to said first-named frequency band, and means responsive jointly to the frequency of said second wave and the frequency of one of said components for maintaining the frequency of said second wave substantially constant on the one of said transmission channels related to said one component.

4. A carrier-wave generating system comprising, means for generating a carrier wave including a carrier-wave component of relatively high and substantially constant frequency and sideband components of substantially constant frequencies and extending over a predetermined frequency band, said components of said carrier wave having equal spacings in the frequency spectrum with relation to each other and the frequencies of said components being individually related to the carrier frequencies of predetermined desired transmission channels, means for generating a second wave having any selectable frequency in a predetermined frequency band equal to said first-named frequency band, and means responsive jointly to the frequency of said second wave and the frequency of one of said components for maintaining the frequency of said second wave substantially constant on the one of said transmission channels related to said one component.

5. A carrier-wave generating system comprising, means for generating a carrier wave including a carrier wave component of relatively high and substantially constant frequency and sideband components of substantially constant frequencies and extending over a predetermined frequency band, means for generating a second wave having any selectable frequency in a predetermined frequency band equal to but displaced by a predetermined value higher in the frequency spectrum from said first-named frequency band, and means responsive jointly to the frequency of said second wave and the frequency of that one of said components which is displaced in the frequency spectrum by a predetermined value from the desired operating frequency of said second wave for maintaining the frequency of said second wave at a substantially constant desired value.
6. A carrier-wave generating system comprising, an oscillator including means for maintaining the frequency thereof substantially constant for generating a carrier wave including a carrier-wave component of relatively high and substantially constant frequency and sideband components of substantially constant frequencies and extending over a predetermined frequency band, means for generating a second wave having any selectable frequency in a predetermined frequency band equal to said first-named frequency band, and means responsive jointly to the frequency of said second wave and the frequency of that one of said components which is related in a predetermined manner to the desired operating frequency of said second wave for maintaining the frequency of said second wave at a substantially constant desired value.
7. A carrier-wave generating system comprising, a piezoelectric crystal-controlled oscillator for generating a carrier wave including a carrier-wave component of relatively high and substantially constant frequency and sideband components of substantially constant frequencies and extending over a predetermined frequency band, means for generating a second wave having any selectable frequency in a predetermined frequency band equal to said first-named frequency band, and means responsive jointly to the frequency of said second wave and the frequency of that one of said components which is related in a predetermined manner to the desired operating frequency of said second wave for maintaining the frequency of said second wave at a substantially constant desired value.
8. A carrier-wave generating system comprising, means for generating a carrier wave including a carrier-wave component of relatively high and substantially constant frequency and sideband components of substantially constant frequencies and extending over a predetermined frequency band, means for generating a second wave having any selectable frequency in a predetermined frequency band equal to but displaced by a predetermined value in the frequency spectrum from said first-named frequency band, means for tuning said second-named generating means approximately to a desired operating frequency and for selecting that one of said carrier-wave components which is displaced in the frequency spectrum by the said predetermined value from said desired operating frequency, and means responsive jointly to the frequency of said second wave and the frequency of said selected component for establishing and maintaining the frequency of said second wave more accurately at said desired operating frequency.
9. A carrier-wave generating system comprising, means for generating a carrier wave including a carrier-wave component of relatively high and substantially constant frequency and sideband components of substantially constant frequencies and extending over a predetermined frequency band, means including an adjustable tuning element for generating a second wave having any selectable frequency in a predetermined frequency band equal to but displaced by a predetermined value in the frequency spectrum from said first-named frequency band, selector means for selecting a desired one of said carrier-wave components, means for operating said adjustable tuning element and said selector means in unison for tuning said second-named generating means approximately to a desired operating frequency and for selecting that one of said carrier-wave components which is displaced in the frequency spectrum by the said predetermined value from said desired operating frequency, and means responsive jointly to the frequency of said second wave and the frequency of said selected component for establishing and maintaining the frequency of said second wave more accurately at said desired operating frequency.
10. A carrier-wave generating system comprising, means for generating a carrier wave having a relatively high and substantially constant frequency, means for generating a modulation signal having frequency components of substantially constant frequencies and predetermined spacing relative to each other, means for modulating said carrier wave with said modulation signal to derive a modulated carrier wave including a carrier-wave component and sideband components extending over a predetermined frequency band.
11. A carrier-wave generating system comprising, means for generating a carrier wave having a relatively high and substantially constant frequency, means for generating a modulation signal having frequency components of substantially constant frequencies and having frequency spacings relative to each other corresponding to the frequency spacings between predetermined desired transmission channels, means for modulating said carrier wave with said modulation signal to derive a modulated carrier wave including a carrier-wave component and sideband components extending over a predetermined frequency band and being individually related to the carrier frequencies of said predetermined desired transmission channels, means for generating a second wave having any selectable frequency in a predetermined frequency band equal to said first-named frequency band, and means responsive jointly to the frequency of said second wave and the frequency of one of said components of said modulated carrier wave for maintaining the frequency of said second wave substantially constant on the one of said transmission channels related to said one component.

12. A carrier-wave generating system comprising, means for generating a carrier wave having a relatively high and substantially constant frequency, means for generating a modulation signal having frequency components of substantially constant frequencies and having equal frequency spacings relative to each other and corresponding to equally-spaced predetermined desired transmission channels, means for modulating said carrier wave with said modulation signal to derive a modulated carrier wave including a carrier-wave component and sideband components extending over a predetermined frequency band and being individually related to the carrier frequencies of said predetermined desired transmission channels, means for generating a second wave having any selectable frequency in a predetermined frequency band equal to said first-named frequency band, and means responsive jointly to the frequency of said second wave and the frequency of one of said components of said modulated carrier wave which is displaced in the frequency spectrum by a predetermined selectable value from said first wave for maintaining the frequency of said second wave substantially constant on the one of said transmission channels related to said one component.

13. A carrier-wave generating system comprising, means for generating a carrier wave having a relatively high and substantially constant frequency, means for generating a signal having a frequency equal to the frequency spacing between equally-spaced desired transmission channels, means for deriving from said signal a modulation signal having frequency components which are harmonically related to said signal, means for modulating said carrier wave with said modulation signal to derive a modulated carrier wave including a carrier-wave component and sideband components extending over a predetermined frequency band and being individually related to the carrier frequencies of said desired transmission channels, means for generating a second wave having any selectable frequency in a predetermined frequency band equal to said first-named frequency band, and means responsive jointly to the frequency of said second wave and the frequency of one of said components of said modulated carrier wave for maintaining the frequency of said second wave substantially constant on the one of said transmission channels related to said one component.

14. A carrier-wave generating system comprising, means for generating a plurality of carrier waves each including a carrier-wave component of relatively high and substantially constant frequency and sideband components of substantially constant frequencies and extending over a predetermined frequency band, the frequencies of the components of each of said carrier waves being individually related to the carrier frequencies of predetermined desired transmission channels and the channels related to the frequencies of the components of a given one of said carrier waves being different from but intervening between the transmission channels related to the others of said carrier waves, means for generating a second wave having any selectable frequency in a predetermined frequency band equal to the combined frequency bands of said first-named carrier waves, and means responsive jointly to the frequency of said second wave and the frequency of one of said components for maintaining the frequency of said second wave at a substantially constant desired value, thereby

5 to maintain said second wave on the one of said transmission channels related to said one component.

15. A carrier-wave generating system comprising, means for generating any selectable one of a plurality of carrier waves each including a carrier-wave component of relatively high and substantially constant frequency and sideband components of substantially constant frequencies and extending over a predetermined frequency band, the frequencies of the components of each of said carrier waves being individually related to the carrier frequencies of predetermined desired transmission channels and the channels related to a given one of said carrier waves being different from but intervening between the transmission channels related to the others of said carrier waves, means for generating a second wave having any selectable frequency in a predetermined frequency band equal to the combined frequency bands of said first-named carrier waves, and means responsive jointly to the frequency of said second wave and the frequency of one of said components for maintaining the frequency of said second wave at a substantially constant desired value, thereby to maintain said second wave on the one of said transmission channels related to said one component.

16. A carrier-wave generating system comprising, means including at least one oscillator having means for maintaining the frequency thereof substantially constant for generating a plurality of carrier waves each including a carrier-wave component of relatively high and substantially constant frequency and sideband components of substantially constant frequencies and extending over a predetermined frequency band, the frequencies of the components of each of said carrier waves being individually related to the carrier frequencies of predetermined desired transmission channels and the channels related to a given one of said carrier waves being different from but intervening between the transmission channels related to the others of said carrier waves, means for generating a second wave having any selectable frequency in a predetermined frequency band equal to the combined frequency bands of said first-named carrier waves, and means responsive jointly to the frequency of said second wave and the frequency of one of said components for maintaining the frequency of said second wave at a substantially constant desired value, thereby to maintain said second wave on the one of said transmission channels related to said one component.

17. A carrier-wave generating system comprising, piezoelectric crystal-controlled oscillator means for generating a plurality of carrier waves each including a carrier-wave component of relatively high and substantially constant frequency and sideband components of substantially constant frequencies and extending over a predetermined frequency band, the frequencies of the components of each of said carrier waves being individually related to the carrier frequencies of predetermined desired transmission channels and the channels related to a given one of said carrier waves being different from but intervening between the transmission channels related to the others of said carrier waves, means for generating a second wave having any selectable frequency in a predetermined frequency band equal to the combined frequency bands of said first-named carrier waves, and means responsive jointly to the frequency of said second wave and the frequency of said second wave and the fre-

quency of one of said components for maintaining the frequency of said second wave at a substantially constant desired value, thereby to maintain said second wave on the one of said transmission channels defined by said one component. 5

18. A carrier-wave generating system comprising, means for generating a plurality of carrier waves each including a carrier-wave component of relatively high and substantially constant frequency and sideband components of substantially constant frequencies and extending over a predetermined frequency band, the frequencies of the components of each of said carrier waves being individually related to the carrier frequencies of predetermined desired transmission channels and the channels related to a given one of said carrier waves being different from but intervening between at least a portion of the transmission channels related to at least one other of said carrier waves, means for generating a second wave having any selectable frequency in a predetermined frequency band equal to the combined frequency bands of said first-named carrier waves, and means responsive jointly to the fre- 25

quency of said second wave and the frequency of one of said components for maintaining the frequency of said second wave at a substantially constant desired value, thereby to maintain said second wave on the one of said transmission channels related to said one component.

19. A carrier-wave generating system comprising, means for generating a carrier wave including a carrier-wave component of relatively high and substantially constant frequency and sideband components of substantially constant frequency and extending over a predetermined frequency band, means for generating a second wave having any selectable frequency in a predetermined frequency band equal to said first-named frequency band, and means responsive jointly to the frequency of said second wave and the frequency of that one of said components of said carrier wave which is related in a predetermined manner to the desired operating frequency of said second wave for maintaining the frequency of said second wave at a substantially constant desired value.

NELSON P. CASE.

Certificate of Correction

April 16, 1946.

Patent No. 2,398,694.

NELSON P. CASE

It is hereby certified that errors appear in the printed specification of the above numbered patent requiring correction as follows: Page 5, first column, line 39, for "exclusive" read *exclusion*; page 8, first column, lines 22 to 24, claim 12, strike out the words "which is displaced in the frequency spectrum by a predetermined selectable value from said first wave"; page 9, first column, line 5, claim 17, for "defined by" read *related to*; and that the said Letters Patent should be read with these corrections therein that the same may conform to the record of the case in the Patent Office.

Signed and sealed this 15th day of October, A. D. 1946.
